(57) **CLAIM**

The ornamental design for a bulk chute feeder, as shown and described.

DESCRIPTION

FIG. 1 is a perspective view of the bulk chute feeder of the present invention.

FIG. 2 is a top view thereof.

FIG. 3 is a side view thereof; and,

FIG. 4 is a front view thereof.

The features shown in broken lines are shown for illustrative purposes only and form no part of the claimed design. The left side view is identical to the right side view and is therefore not included as an independent figure. The bottom and the rear views form no part of the design and are therefore not included as independent figures.
